UNITED STATES PATENT OFFICE.

CHARLES E. ADAMSON, OF DERBY, CONNECTICUT, ASSIGNOR TO ADDRESSOGRAPH COMPANY, OF CHICAGO, ILLINOIS, A CORPORATION OF ILLINOIS.

RIBBON-FEEDING MECHANISM FOR DUPLICATING-MACHINES.

1,198,505.

Specification of Letters Patent. Patented Sept. 19, 1916.

Application filed May 2, 1913, Serial No. 764,976. Renewed January 24, 1916. Serial No. 74,015.

To all whom it may concern:

Be it known that I, CHARLES E. ADAMSON, a citizen of the United States, residing at Derby, in the county of New Haven and State of Connecticut, have invented new and useful Improvements in Ribbon-Feeding Mechanism for Duplicating-Machines, of which the following is a specification.

My invention relates to ribbon feeding mechanism for duplicating machines and more particularly to that type of machine designed for imitating typewritten letters in quantities from a single type form adapted to have its printing surface reproduced through an inked ribbon.

In machines of this kind the method usually employed is to wind the ribbon from one roll or spool onto another and by means of the mechanisms now employed the amount of rotation of the take-up roll or spool is always the same preparatory to printing a new sheet. Consequently, as the ribbon becomes wound upon the take-up roll or spool the size of the roll or spool with that portion of the ribbon wound thereon becomes gradually enlarged in diameter so that with each movement of the roll or spool increasing portions in length of the ribbon are passed over the type form, thus feeding the ribbon unevenly over the form and causing the sheets of paper being printed to run from light to dark impressions on a single job. In other words, such uneven rotation of the take-up roll causes uneven feeding of the ribbon which results in imperfect impressions being taken from the ribbon-covered type form; consequently, when the impression is perfect at the beginning of operations it becomes imperfect by reason of being too heavy or too light later during the operation of the machine, depending upon the amount of ribbon on the take-up roll when starting operation and whether or not reverse movement of the ribbon is necessary during such operations. Regardless of the amount of ribbon on the take-up roll and the necessity for reversing the direction of travel of the ribbon when commencing operation on a job requiring a number of impressions, if the impression is adjusted to perfection at commencement of operations, it will vary by reason of the uneven feeding of the ribbon over the printing form due to the equal intermittent movements of the take-up roll.

The primary object of my invention is to overcome the objections above noted and to this end I employ means serving to rotate the take-up roll intermittently and in degrees proportionate to the gradually increasing lengths of the ribbon being wound upon the gradually increasing diameter of the take-up roll with its ribbon thereon during each complete revolution of the roll.

Other objects of my invention are to provide a ribbon feeding mechanism which can be easily and conveniently reversed, and to provide means whereby the ribbon may be retained in an immovable position over the type form so that the machine may be continued in operation without feeding the ribbon; this being desirable when, for instance, the quantity of paper provided for printing becomes exhausted or when for any other reason the operator does not place paper on the ribbon covered printing form, it of course being understood that suitable means is provided to move the impression element out of contact so that during the times of its traversing the ribbon-covered type form without a sheet of paper being placed upon the form it will not become smudged by contact with the ribbon.

With these and other objects in view my invention consists in the provision of means within machines of the kind referred to whereby the ribbon is fed over the printing form by equal intermittent movements so as to assure even impressions at all times.

It further consists in means for holding the ribbon feeding mechanism in inactive position, and it further consists in the arrangement and combination of devices and in the construction of parts to be herein-after described and particularly pointed out in the subjoined claims.

In the drawings, Figure 1 is a top plan view of a printing or duplicating machine such as my improved ribbon feeding mechanism may be applied to, the inking ribbon being shown broken away to better illustrate the printing form beneath, and the machine being merely representative of that class of machines to which my invention is applicable. Fig. 2 is a longitudinal section taken on line $v-v$, Fig. 1. Fig. 3 is an inverted view of the machine without the stand or support shown in Fig. 2. Fig. 4 is an enlarged side elevation of one end of the machine proper showing the side members

100

105

110

broken away to better illustrate a portion of the feeding mechanism in rear thereof. Fig. 5 is an enlarged longitudinal section taken on line $w-w$, Fig. 1, parts of the impression carriage being omitted for convenience. Fig. 6 is an enlarged transverse section taken on line $x-x$, Fig. 2, the ribbon roll or spool being omitted. Fig. 7 is a transverse section taken on line $y-y$, Fig. 2. 10 Fig. 8 is a detached perspective view of one end of the frame with the weighted oscillating feeding arm pivoted thereto and the regulator bar connected therewith. Fig. 9 is a transverse section taken on line $z-z$, Fig. 2. 15 Fig. 2.

Referring now to the drawings in detail, like numerals of reference refer to like parts in the several figures.

10 designates a stand or support upon 20 which the machine proper is supported, the stand or support herein shown being constructed of wood and having a casting 11 at its upper edge at each of its four corners to receive the legs 12 of the frame. The frame 25 comprises side members 13 from which the legs 12 depend and the type bed 14 bridging the space between said side members. At each end the type-bed 14 has a transverse rib 15 and a similar rib 16 is provided at an 30 intermediate point.

Placed upon the type-bed 14 is a type-chase 17 in which the type-form 18 is held, said form being of individual assembled type, zinc etchings, or any other objects or 35 devices capable of permitting an impression to be obtained therefrom. The frame has guide bars 19 at the upper edges of its side members for the purpose of guiding a traveling carrier or carriage 20, which carrier 40 in the particular form of machine shown, has opposite ends of sprocket chains 21 or other suitable flexible operating elements attached thereto, said chains passing around wheels 22 arranged in pairs on shafts 23, 24 45 journaled in the frame at opposite ends thereof, the shaft 23 being a single shaft arranged at one end of the frame and the shafts 24 being stub-shafts at the other end.

50 In the drawings I have shown a flat bed for the printing form, but it is clear that any other form of bed may be used, and while the chains 21 employed are so attached to the traveling carrier or carriage 20 that upon operated they cause said carrier or carriage to reciprocate with reference to the type form it will be apparent that my improved ribbon feeding mechanism will be applicable to duplicating or printing machines in which the carrier may travel in other than a reciprocating manner. Mounted for rotation in said carrier or carriage is an impression roller 25 which is adapted to travel in contact with an inked ribbon 26 lying in contact with the type-form and adapted to be moved intermittently there-

over so as to at all times present a new printing surface to the characters constituting the type-form. This inked ribbon is wound upon a rotatable roll or spool 27 and adapted to be unwound therefrom and be wound 70 upon a rotatable roll or spool 28.

For the purpose of moving the inked ribbon over the type-form, feeding mechanism is employed to cause the ribbon to be wound upon one spool while the other allows the 75 ribbon to become unwound therefrom. As shown in Fig. 2, the roll or spool 28 acts as the take-up roll since the ribbon, upon operation of the machine, travels in the direction of the arrow marked A, but when the ribbon travels in the opposite direction, the roll or spool 27 becomes the take-up roll. 80

The impression carrier or carriage 20 may be operated in any suitable manner, but I have shown a main driving shaft 29 arranged transversely and journaled in hangars 30 depending from the side members 13 of the frame, said shaft having at one end a belt pulley 31 and also a handle 32 whereby it may be rotated to cause actuation of 85 the machine. When it is desired to actuate the machine by means of power, it may be driven by means of any suitable motor from which power may be imparted to the pulley 31 with a suitable belt or in any other manner. At the opposite end of the main driving shaft 29 is a pinion 33 which rotates in mesh with an internal gear 34 secured to a transverse shaft 35 also journaled in the side members 13 of the frame. A pitman 36 has one of its ends secured eccentrically to the exterior surface of said internal gear by means of a wrist pin 37, the opposite end of said pitman being pivotally secured to mechanism intervening therebetween and the 90 one piece shaft 23 so as to rotate the same, and as this forms no part of the present invention it is not thought necessary to illustrate or describe the same in detail. It should therefore suffice to state that the rotation of the shaft 23 is brought about in any suitable manner and causes the chains 21 to be drawn back and forth over the pair of sprocket wheels 22 on said one piece shaft 23 which in turn impart rotary motion to 95 the wheels 22 on the stub shafts 24, said last-mentioned wheels being idlers and serving merely to guide the chains so as to cause a reciprocating movement to be imparted to the traveling carrier or carriage. The impression roller 25, by suitable mechanism forming no part of my present invention, is caused to be moved into contact with the ribbon-covered type-form having a sheet of paper placed thereon when said carrier or 100 carriage moves in one direction and to cause said impression roller to be moved out of contact with said ribbon-covered type-form when moving said carrier or carriage in its opposite direction. In other words, during 105

the movement of the carrier or carriage 20 in one direction the impression roller 25 is in printing position, while when the carrier moves in an opposite direction said impression roller is out of printing position. Suitable paper delivering mechanism, such as is indicated at 38 may be provided to remove the printed sheets from the machine while the impression roller is traveling out of printing position. The parts thus far described may be of any desired construction and arrangement and are illustrated and described merely to make clear the operation of one form of printing or duplicating machine with which my improved ribbon feeding mechanism is adapted to be used.

The ribbon rolls or spools 27, 28 have their opposite ends supported in socket members 39, 40, one of said members for each 20 spool being secured to a rotatable spindle 41 journaled in one side member 13 of the frame, and the other forming part of a rod 42 passing through the other side member of said frame, said rod having a stop nut or 25 collar 43 secured to its outer end and bearing against the exterior face of the frame. Surrounding each of said last-mentioned rods is a coil spring 44 bearing with one end against the socket 40 and with its other end 30 against the interior face of the adjacent side member 13, thus holding said rod 42 in its innermost position. The rods 42 may be drawn outward against the action of the springs 44 to permit the ready insertion of 35 the ribbon spools or rolls thereinto or their removal therefrom. Each socket 39 has a pin 45 arranged transversely therein which is adapted to fit in a kerf formed at the opposite end of the roll or spool so that the latter 40 will be compelled to rotate with the shaft or spindle 41 but it is free to rotate within the socket member 40 of the rod 42. The shaft or spindle 41 with its socket member and the rod 42 with its socket member 45 serve as a pair of supports for the roll or spool, and a pair of these are arranged at each end of the frame.

Secured to each of the shafts or spindles 41 is a ratchet wheel 46, and a feeder 50 in 50 the form of a weighted arm is loosely mounted on each of said shafts and is adapted to be actuated by some traveling part or member of the machine and in turn cause actuation of the shaft 41, which latter, through its socket member, causes rotation of the ribbon roll or spool supported therein. For the purpose of causing actuation of the shafts 41, each of the feeders 50 is formed to oscillate thereon. Each feeder 60 comprises a hub 51 from which extends an arm 52 having its upper end cut or formed diagonally, as at 53, and a second or weighted arm 54 arranged at an angle to the arm 52 and constructed so that its weight serves 65 to maintain the arm 52 in substantially ver-

tical position, as best shown in Fig. 4. Each of the feeders may therefore be said to consist of a weighted oscillating arm. Each of these weighted oscillating arms has a dog 55 pivotally secured thereto whose actuating end 56 is adapted to engage the teeth of its coöperating ratchet wheel, said dog being normally held in engagement with said ratchet wheel by means of an expansion spring 57 interposed between it and the arm 54 of the feeder. As shown in dotted lines in Fig. 4, the upper end of the weighted oscillating arm at one end of the machine is in the path of a lug or ear 58 on the carrier or carriage and some other portion of a traveling part of the machine is adapted to engage in a like manner the weighted oscillating arm at the opposite end of the machine, so that when the carrier or carriage moves in one direction and approaches the end of its movement in such direction, the lug 58 or other similar acting part of the machine engages the beveled end of the first-mentioned oscillating arm and causes the same to swing through an arc of a circle, thereby elevating the weighted arm 54 and causing the dog 55 to rotate its coöperating ratchet wheel 46. The latter, by reason of its being secured to the shaft or spindle 41 having the socket member 39 thereon, compels the coöperating ribbon roll or spool to be rotated, thus winding up the ribbon. It is to be noted that when one of the ribbon spools is being wound up by one of the feeders 50, the other feeder at the opposite end of the machine is inactive, that is to say, it is moved out of the path of the part adapted to actuate it.

In order to prevent retrograde movement of each of the ratchet wheels a spring dog 59 is secured to the bed 14 of the frame, as at 90, and extends therefrom to contact with the teeth of the ratchet wheel, it extending over the acting end of the dog 55, as best shown in Fig. 4.

Projecting inward from the weighted arm 54 of each feeder is a pin or stud 60 which is straddled by a pair of lugs 61 formed on one end of a controlling lever 62. Each of said controlling levers is pivotally secured to the adjacent rib 15 on the type-bed, as at 63, and has a short extension 64 beyond its pivotal point which is adapted to come in contact with the underside of the type-bed when the opposite side of the lever is in its lowermost position. Each of these levers has a laterally extending arm 65 which is adapted to project outward therefrom and lie in contact with that portion of the inked ribbon wound around the roll or spool, the arm 65 being arranged near that end of the lever adjacent its coöperating feeder. By reason of the arm 65 lying in contact with the inked ribbon wound about the ribbon roll or spool, the position of the controlling lever is gov-

erned thereby and as the ribbon roll or spool at one end of the machine is being rotated and an increasing portion of the ribbon becomes wound around it, the arm 65 is elevated, which in turn causes the actuating end of the controlling lever to be elevated and through its action upon the pin 60 the weighted arm 54 of the feeder is elevated. This action causes the arm 52 to be swung at a greater inclination, which is always in proportion to the position of the arm 65 controlled by the number of convolutions of the inked ribbon about its spool. The greater the inclination of the arm 52 the later in the actuation of the impression carrier or carriage will the part 58 thereof engage said arm, consequently, the extent of movement of the arm 52 is diminished in exact proportions to the increased quantity of the ribbon wound about the ribbon roll or spool so that substantially the same amount of feed will be imparted to the ribbon regardless of the increasing diameter of the ribbon-covered roll or spool.

As shown in the drawings, the feeders are arranged at diagonally opposite corners of the type-bed, one feeder being employed for each ribbon spool, and while I have described the construction and actuation of one feeder it will suffice for the other, as both are alike with the exception that the weighted arm 54 of one of the feeders has an outwardly-directed pin 66 secured thereto, best shown in Figs. 3 and 4, which is adapted to be engaged by an arm 67 secured to a rock-shaft 68 arranged transversely underneath the frame of the machine one side member of said frame having a depending portion 69 formed thereon and the other having a bearing 70 secured thereto, in which are journaled the end portions of the shaft 68. At one end of the shaft is an actuating lever 71 having a handle 72 for conveniently manipulating the same, and adapted for coöperation with said actuating lever is a plate or other retaining device 73 which is secured to the adjacent side member 13, said plate having its ends converging toward the axis of the shaft 68 and adapted to be engaged by said actuating lever.

As shown in Fig. 4, said lever engages one end of the plate 73, thus being held in one of its two inclined positions. When in this position it has rocked the shaft 68 to bring the arm 67 thereof in contact with the pin 66 of the adjacent feeder and caused the weighted arm of the latter to be elevated and the acting arm thereof to be lowered out of the path of the part adapted to cause actuation of the same. It will be noticed that by reason of the weighted arm 54 of the feeder being elevated, the heel 74 of the dog is caused to engage the underside 65 of the bed plate, or it may be arranged to

engage some other fixed part of the machine, such engagement resulting in compressing the spring 57 and raising the acting end of the dog out of engagement with the teeth of the coöperating ratchet wheel 46. At the same time the acting end of said dog is brought in engagement with the under face of the spring pawl 59 to disengage the latter from the ratchet wheel, thus leaving the ratchet wheel and its coöperating ribbon spool free to rotate. This position of the parts is brought about when the ribbon is fully wound upon the adjacent ribbon spool, and when the parts of the feeder at one end of the machine are in such position, the feeder at the opposite end of the machine is set for actuation. For this purpose the shaft 68 has an arm 75 extending therefrom to which is secured one end of a chain 76 which has its other end secured to the weighted arm of the feeder at said opposite end of the machine, as at 77. When the arm 75 is swung in the position shown in Fig. 4 said chain is loosened sufficiently to permit the weighted arm of the feeder to gravitate and throw the acting arm into the path of the contacting part 58 on the impression carrier or carriage and, consequently, with each complete reciprocating movement of said carrier or carriage the feeder is actuated until the entire ribbon is unrolled from the roll at the opposite end and wound upon the roll actuated by said feeder. It will then be found necessary to swing the actuating lever 71 from the position shown in full lines in Fig. 4 to that shown in dotted lines, thus bringing said lever in contact with the opposite end of the plate 73. This swings the arm 67 out of contact with the pin 66 on the feeder and allows the latter to assume its acting position. At the same time the arm 75 is swung to the position shown in dotted lines in Fig. 4 and has drawn upon the chain 76 so as to elevate the weighted arm of the feeder at the opposite end of the machine, thereby causing the feeder at the adjacent end of the machine to be depressed so as to assume a position out of the path of the lug part 58 on the carrier or carriage.

When it is found desirable to permit the machine to continue operation without feeding the ribbon over the type-form, a lever 78 which may be pivotally secured to the support 10 may be elevated. This lever is normally held in depressed position by engaging a tooth on a retainer bar 79 secured to said support. Pivotally secured to said lever with one end is a rod 80 having its other end pivotally connected to one end of a bell-crank lever 81 which is pivotally secured, as at 82, to one of the side members of the frame. The other arm of said bell-crank lever is secured to a rod 83 arranged lengthwise and extending underneath the

type-bed, said last-mentioned rod having pivotal connection with a centrally pivoted lever 84 at one end thereof, said lever having said end connected with one end of a retractile spring 85 whose other end is connected to the rock shaft 68 and, consequently, serves to hold said centrally pivoted lever in position shown in dotted lines in Fig. 3. This, however, is resisted by the operating lever 78 which is engaged with the retainer plate 79, but upon disengaging said lever 78 the spring 85 comes into action and causes said centrally pivoted lever to be swung into the position shown by said dotted lines. Said end of the lever 84 has one end of a chain 87 secured thereto, its other end being attached to the weighted arm of the feeder on the same side of the machine, thus when the lever 78 is released from its retainer plate, the spring, while drawing the centrally pivoted lever 84 into the position shown in dotted lines in Fig. 3, also serves to draw the chain 87 taut, thereby moving said feeder into idle position. The feeder at the opposite side of the machine 25 has one end of a chain 89 secured thereto, whose other end is secured to the opposite end of the centrally pivoted lever 84, thus when said lever is actuated by the spring 85 the chain 89 is drawn taut, but such action of the chain does not necessarily move the coöperating feeder into idle position since, as the parts are shown, it has been in idle position owing to the feeder at the opposite end being in acting position, but in the event of said latter feeder being in idle position and the other being in acting position the chain 89 will cause the last-mentioned feeder to be moved into idle position 40 by reason of the weighted arm of said feeder assuming a lower position than when said feeder is idle.

Having thus described my invention, what I claim is,—

- 45 1. In a duplicating machine, the combination of rotatable spools to which the ends of a ribbon are secured and which ribbon is unwound from one spool and adapted to be wound upon the other, a weighted oscillating feeder arm having its axis coincident with that of said other spool, a ratchet wheel having its axis coincident with the axes of said last-mentioned spool and said weighted oscillating feeder arm, a dog carried by said weighted oscillating feeder arm and adapted to engage said ratchet wheel, means to prevent retrograde movement of said ratchet wheel, and means controlled by the winding up of the ribbon upon said last-mentioned spool to regulate the position of said oscillating feeder arm whereby the extent of rotation of said last-mentioned ribbon spool is governed.
  - 55 2. In a duplicating machine, the combination of an inking device comprising spools
- to which an inked ribbon is secured, said spools being rotatably supported and one end of each spool being secured to a rotatable spindle, a ratchet wheel secured to each of said spindles, a weighted oscillating arm swinging on said spindle, a dog secured to said weighted arm and adapted to coact with said ratchet wheel, a controlling lever pivotally secured and having a portion lying in contact with the ribbon wound upon the adjacent spool so as to cause gradual movement of said controlling lever, and a connection between said controlling lever and said oscillating arm to cause the latter to be positioned in accordance with the gradually changing position of said controlling lever and thus cause diminished movements of said oscillating arm.

3. In a duplicating machine, the combination of an inking device comprising a spool at each end of the machine to which a ribbon is secured, said ribbon being wound upon one of said spools and adapted to be unwound therefrom and wound upon the other, a weighted feeder arm for each spool to actuate the same, a transversely-disposed lever pivotally secured between its ends to said frame, a chain connecting each end of said transversely-disposed lever with one of said feeder arms, a spring serving to retain said transversely-disposed lever in a certain position, and means for moving said last-mentioned lever into another position against the action of said spring, for the purpose described.

4. In a duplicating machine, the combination of an inking device comprising a ribbon spool at each end of the machine, a feeding device to rotate each of said ribbon spools, a transversely-disposed lever pivotally secured between its ends to said machine, flexible connection between opposite ends of said lever and opposite feeding devices, a spring tending to hold said lever at the end of its movement in one direction, means for retaining said lever at the end of its movement in its other direction against the action of said spring, a rock shaft journaled transversely in said frame and having an actuating lever, means engaged by said actuating lever to retain said rock-shaft in one of its positions, an arm secured to said rock-shaft and engaging one of said feeding devices to hold the same in inactive position when said rock-shaft is rocked in one direction, a second arm secured to said rock-shaft, and a flexible connection between said second arm and the other feeding device and serving to hold the latter in inactive position when said rock-shaft is rocked in its other direction.

5. In a duplicating machine, the combination of a ribbon spool at each end of the machine having a ribbon arranged to be unwound from one spool and wound onto

the other, rotatable spindles at opposite ends of the frame to which said ribbon spools are attached to rotate therewith, a ratchet wheel secured to each of said rotatable spindles, a feeder arm loosely mounted on each spindle and having a weighted extension, a dog pivotally secured to each of said weighted extensions and engaging the adjacent ratchet wheels, a spring interposed between each dog and its supporting weighted extension, means to cause each of said feeder arms to be swung out of acting position and the weighted extensions thereof to be swung upwardly whereby the dogs are engaged by the machine and the acting ends thereof disengaged from said ratchet wheels, and a detent pawl extending over the acting end of each dog and adapted to be engaged by the latter to cause its disengagement from said ratchet wheel.

6. In a duplicating machine, the combination of ribbon feeding mechanism comprising a pair of spools upon which a ribbon is wound and means for rotating one of said spools, including a pivoted lever normally biased in one direction, means disposed in the path of said lever and engaging the ribbon on said spool to variably limit the movement of said lever in said direction, a driving connection between said lever and spool, and means for actuating said lever to move it in the opposite direction.

7. In a duplicating machine, the combination of ribbon feeding means comprising a pair of spools upon which a ribbon is wound and means for rotating one of said spools, including a pivoted weighted lever, means disposed in the path of said lever and engaging the ribbon on said spool to variably limit the movement of said lever in one direction, a driving connection between said lever and spool, and means for actuating said lever to move it in the opposite direction.

8. In a duplicating machine, the combination of ribbon feeding means comprising a pair of spools upon which a ribbon is wound and means for rotating one of said spools, including a pivoted weighted lever, a pivoted member provided with means to engage the ribbon on said spool and having an end disposed in the path of said lever to variably limit the movement thereof in one direction, a driving connection between said lever and spool, and means for actuating said lever to move it in the opposite direction.

9. In a duplicating machine, the combination of ribbon feeding means comprising a pair of spools upon which a ribbon is wound and means for rotating one of said spools, including a pivoted weighted lever, means disposed in the path of said lever and engaging the ribbon on said spool to

variably limit the movement of said lever in one direction, a ratchet wheel connected to said spool, a dog on said lever adapted to engage said ratchet wheel, and means for actuating said lever to move it in the opposite direction.

10. In a duplicating machine, an inking device comprising a pair of spools, supporting a ribbon attached to said spools and adapted to be unwound from one and wound upon the other, an oscillatory feeder arm normally biased in one direction, and means engaging the ribbon on one of said spools and disposed in the path of said arm to variably limit its movement in said direction, said arm being adapted to actuate said spool by its movement in the opposite direction.

11. In a duplicating machine, the combination of rotatable spools to which the ends of a ribbon are secured, a weighted oscillatory feeder arm, a ratchet wheel operatively connected to one of said spools and having its axis coincident with the axis of said spool, a dog on said feeder arm adapted to engage said ratchet, means to prevent retrograde movement of said ratchet wheel, means disposed in the path of said feeder arm and engaging the ribbon on said spool to variably limit the movement of said feeder arm in one direction, and means to move said feeder arm in the opposite direction.

12. In a duplicating machine, the combination of rotatable spools to which the ends of a ribbon are secured, an oscillatory feeder arm having its axis coincident with the axis of one of said spools, a ratchet wheel operatively connected to said spool, a dog on said feeder arm adapted to engage said ratchet wheel, a pivoted member disposed in the path of said arm and engaging the ribbon on said spool to variably limit the movement of said arm in one direction, and means for moving said arm in the opposite direction.

13. In a duplicating machine, the combination of rotatable spools to which the ends of a ribbon are secured, an oscillatory feeder arm operatively connected to one of said spools and having its axis coincident with the axis of said spool, means for actuating said feeder arm to move it in one direction, and independent means engaging the ribbon on said spool to variably limit the movement of said feeder arm in the opposite direction.

14. In a duplicating machine, the combination with a frame, of an inking device comprising spools at each end of said frame to which a ribbon is secured, an oscillatory feeder arm for each spool, means for actuating said feeder arms, a transversely disposed lever pivotally secured between its ends to said frame, means con-

necting one of said feeder arms to each end of said lever, a spring to retain said lever in a predetermined position, and means for moving said lever to another position against the action of said spring.

15. In a duplicating machine, the combination with a frame, of an inking device comprising spools at each end of said frame to which a ribbon is secured, an oscillatory feeder arm for each spool, means for actuating said feeder arms, a transversely disposed lever pivotally secured between its ends to said frame, means connecting one of

said feeder arms to each end of said lever, a spring to retain said lever in a predetermined position, and means for moving said lever to another position against the action of said spring.

15. In testimony whereof I have affixed my signature in the presence of two subscribing 20 witnesses.

CHARLES E. ADAMSON.
